UNITED STATES PATENT OFFICE.

GEORGE W. MARTIN, OF PARIS, TEXAS.

FOLDING COOP.

1,231,042.

Specification of Letters Patent. Patented June 26, 1917.

Application filed May 24, 1916. Serial No. 99,595.

To all whom it may concern:

Be it known that I, GEORGE W. MARTIN, a citizen of the United States, residing at Paris, in the county of Lamar and State of Texas, have invented certain new and useful Improvements in Folding Coops, of which the following is a specification.

This invention relates to an improved folding coop and the principal object of the invention is to provide a coop having an improved upper wall construction and also having side walls provided with improved means for pivotally connecting the walls with the top and for releasably connecting the end walls with the side walls.

Another object of the invention is to so construct the coop that the upper wall and side and end walls will be very strong and durable.

Another object of the invention is to so construct the coop that it may be easily and quickly folded or set up.

Another object of the invention is to so connect the bottom with the end walls that the bottom will serve as means for limiting the inward movement of the end walls.

This invention is illustrated in the accompanying drawings, wherein:—

Figure 1 is a perspective view of the improved coop in the set-up position.

Fig. 2 is a view in elevation of the improved coop when folded.

Fig. 3 is a fragmentary view showing the manner of connecting the walls with the top of the coop.

The top wall of this coop is provided with side bars 10 and end bars 11, the side bars and end bars being connected by longitudinally and transversely extending cross bars 12 and 13 secured to the side and end bars and having their intermediate portions extending in cross relation and connected. Reinforcing and bracing wires 14 and 15 are also provided, the wires extending as shown in Fig. 1 and having their end portions twisted about the side and end bars. A closure door 16 is hingedly connected with one of the cross bars 13 by means of eye hinges 17 and is supported in the closed position by the supporting wire 18 connected with two of the longitudinally extending bars 12.

The side walls and end walls are each provided with a longitudinally extending bar 19 and transversely extending bars 20, the transversely extending bars carrying eyes 21

engaging the side and end bars 10 and 11 of the upper wall to pivotally connect the side and end walls with the upper wall. It should be noted that the transversely extending bars 20 of the end walls do not extend to the longitudinally extending bar 19 thereof but terminate short thereof and have their ends connected with a longitudinally extending bar 22 secured to the bars 20 of the end walls. Therefore a space is left between the longitudinally extending bars 19 and 22 through which the ends of bottom 23 may pass. This bottom rests upon the bars 19 of the end walls and is provided with cross strips 23' engaging the bar 19 and thus limiting the inward movement of the end walls.

When this coop is set up the side and end walls are swung downwardly to extend from the upper wall and after the end walls have been connected with the side walls by means of hooks 24, the bottom is put in place through the openings between bars 19 and 22 and is then forced downwardly thus bringing the hooks into tight engagement with the transversely extending bars 20 of the side walls. These hooks 24 are formed of resilient material and therefore the side walls will be securely but releasably held in engagement with the end walls.

When folding this coop, the bottom is drawn outwardly and the side and end walls are then swung upon the top wall. The coop will then be folded into a compact mass and can be very easily shipped or carried from one place to another.

I have therefore provided a folding crate which will be very serviceable in that it can be very easily set up or folded and have further provided a crate which while it will be light and easy to handle will be very strong and durable. It should be especially noted that the top and side and end walls due to the cross wires 14 and 15 of the upper wall and wires 25 and 26 of the side and end walls will be securely braced and prevented from becoming broken or worked out of shape. It should be further noted that wire netting may be provided for the top and walls, the netting being placed beneath wires 14, 15, 25 and 26 to securely hold it in place. In the drawing only one of the side walls has been shown provided with the bracing wires 25 and 26 but it is understood that both side walls and both end walls will be provided with these wires.

What is claimed is:—

1. A folding coop comprising an upper wall, side and end walls, said side and end walls being provided with transversely extending bars, eyes carried by said bars and engaging said upper wall to pivotally connect the side and end walls with the upper wall, said end walls including longitudinally extending bars extending in spaced relation to the outer ends of the end walls to provide clearance spaces, a bottom having its ends extending into the spaces provided in the end walls, and means releasably connecting said end walls with said side walls.
- 10 2. A folding coop including an upper wall, side and end walls pivotally connected with said upper wall, certain of said last mentioned walls being provided with transversely extending pockets, a bottom having its end portions fitting into said pockets and provided with cross strips for engaging the walls to limit the inward movement thereof, and means for releasably connecting the side and end walls.
- 15 3. A folding coop comprising an upper wall, side and end walls, means pivotally connecting the side and end walls with the upper wall, side and end walls including longitudinally extending bars extending in spaced relation to the outer ends of the end walls to provide clearance spaces, a bottom having its ends extending into the spaces provided in the end walls, and means releasably connecting said end walls with said side walls.
- 20 4. A folding coop comprising an upper wall, side and end walls, pivotally connected with the upper wall, said end walls including longitudinally extending bars extending in spaced relation to the outer ends of the end walls to provide clearance spaces and having hooks at their ends to releasably connect the end walls with the side walls, and a bottom having its ends extending in to the spaces provided in the end walls.
- 25 5. A folding coop comprising an upper wall, side and end walls, pivotally connected with the upper wall, said end walls including longitudinally extending bars extending in spaced relation to the outer ends of the end walls to provide clearance spaces, a bottom having its ends extending into the spaces provided in the end walls, and means releasably connecting said end walls with said side walls.

30 connecting the side and end walls with the upper wall, said end walls including longitudinally extending bars extending in spaced relation to the outer ends of the end walls to provide clearance spaces, a bottom having its ends extending into the spaces provided in the end walls, and means releasably connecting said end walls with said side walls.

35 4. A folding coop comprising an upper wall, side and end walls, pivotally connected with the upper wall, said end walls including longitudinally extending bars extending in spaced relation to the outer ends of the end walls to provide clearance spaces and having hooks at their ends to releasably connect the end walls with the side walls, and a bottom having its ends extending in to the spaces provided in the end walls.

40 5. A folding coop comprising an upper wall, side and end walls, pivotally connected with the upper wall, said end walls including longitudinally extending bars extending in spaced relation to the outer ends of the end walls to provide clearance spaces and having hooks at their ends to releasably connect the end walls with the side walls, and a bottom having its ends extending in to the spaces provided in the end walls.

45 In testimony whereof I affix my signature in presence of two witnesses.

GEORGE W. MARTIN.
